(57) **CLAIM**

The ornamental design for a lens for infrared imaging, as shown and described.

DESCRIPTION

FIG. 1 is a perspective view of a first embodiment of the lens for infrared imaging showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a perspective view of a second embodiment of the lens for infrared imaging showing our new design; and,

FIG. 9 is a front view of FIG. 8.

The portions shown in broken lines in the drawings depict environmental subject matter only and form no part of the claimed design.

(Continued)

The portions shown in black in the FIGS. **1, 2, 8 and 9** indicate the color black (PANTONE Proc. Black).
